UNITED STATES PATENT OFFICE.

SIDNEY HOLE, OF ALBOURNE, HASOCKS, ENGLAND.

RECEIVING APPARATUS FOR ATTACHMENT TO HOUSE DOORS, WALLS, OR OTHER PARTS OF BUILDINGS.

Application filed December 30, 1926, Serial No. 158,058, and in Great Britain January 7, 1926.

This invention relates to receiving apparatus for attachment to house doors, walls or other parts of buildings, for receiving parcels, postal packages and other articles of all kinds, particularly such as have to be delivered by messengers at houses, and the kind of parcel-receiving apparatus to which the invention relates is that comprising a container, having an opening in one side, that is guided to move in proximity to an aperture in the wall, for example a door, through which a parcel is to be received, and a closure member for the aperture which can be actuated from outside the door and serves to control movement of the container in relation to the aperture. Such a container may be divided into two or more compartments having each a lateral opening for receiving goods through the aperture.

This invention has for its object to provide an improved construction of parcel-receiving apparatus of the kind described which shall be simple to construct and reliable in operation, and can be readily applied to existing doors, for the reception of the above-mentioned articles, hereinafter referred to generally as parcels.

According to a primary feature of the invention there is provided parcel-receiving apparatus of the kind described wherein the container has a single compartment, characterized in that the container, urged by gravity or a spring to move in one direction, is normally held against movement in said direction by the closed closure member or a part operatively connected (e. g. movable) therewith, which closure member when opened permits the container to move independently of it in said direction on to or against a support by which it is retained in a position ready for the reception of a parcel through the aperture.

According to another feature of the invention the closure member (e. g. a hinged flap) carries a locking device (e. g. a spring-controlled latch) so arranged as to tend to lock the closure member in its closed position when it has been closed, but normally serves to support the container and is held by the latter in an unlocking position that permits the closure member to be opened.

According to a further feature of the invention the container comprises a plurality of compartments having each an opening at the same side of the container, and a plu-

rality of holding members (for example a plurality of detents, one for each compartment) movably mounted on the container are provided for co-acting successively with the closure member or the locking device on the latter, and thereby retaining the container successively in different positions, in each of which positions one compartment has its opening opposite said aperture. This construction provides for several parcels being left by several messengers in succession without having to clear the container after each delivery.

According to yet another feature of the invention said holding means (e. g. detents) move each into operative position in relation to the closure member, or a part (e. g. a latch) carried thereby, when the opening of the respective compartment moves into register with the said aperture.

According to still another feature of the invention, locking means is provided for automatically locking the closure member of the aperture in all positions of the container except one wherein the container is intended to receive a parcel through the aperture.

Other features of the invention relate to means for guiding the container, ratchet mechanism for preventing the container from being moved by an unauthorized person in a direction opposite to that in which it moves when loaded, means for returning the container into its starting position, and shock-absorbing means for breaking the fall of the container as it descends from a higher position to a lower.

Further features of the invention will be described hereinafter and pointed out in the claims.

One embodiment of the invention is diagrammatically illustrated by way of example in the accompanying drawing, wherein—

Figure 1 is a perspective view of a house door having applied thereto one construction of parcel-receiving apparatus according to the invention comprising a container movable vertically on the inner face of the door;

Figure 2 is a rear elevation of the container and door, partly broken away, as seen from the back of the door;

Figure 3 is a horizontal section taken on the bent line 3—3 in Figure 2;

Figure 4 is a detail vertical sectional view, enlarged, taken on the line 4—4 in Figure 1.

2 showing escapement mechanism for the container in one position;

Figure 5 is a view corresponding to Figure 4 but showing the same mechanism in another position;

Figure 6 is a detail side elevation showing one form of shock-absorbing device for the container, and

Figure 7 is a detail side elevation of 10 mechanism for preventing the container from being lifted by an unauthorized person.

Like reference numerals designate like 15 parts throughout the several views.

Referring first to Figure 1, a wall 30, which is shown as a door, such as the outer door of a dwelling house, has near the middle of it an aperture 31 for permitting articles, such as parcels, bottles of milk and 20 the like to be passed through it into a container 10, mounted behind the door. A metal frame 32, for example of cast iron, is secured in the aperture and a closure-member 33 in the form of a flap is hinged to the 25 bottom of the frame so as to fold up, and close the aperture or to fold down and rest horizontally to constitute a shelf level with the bottom of the aperture outside the door.

As shown in Figure 2, the vertical rectangular container 10 has a bottom 11, top 12, back wall 13 in the form of a hinged door, and side walls 14, 15, but no front wall. It is divided by partition walls 16, 17, 18 into four compartments each open at the 30 front, namely two long horizontal compartments 19, 20, extending each from side to side of the container, a vertical compartment 21 extending down from the partition 17 through the bottom 11 of the container 40 into a box-like pocket 22 below the bottom 11 at one side of the container, and a shorter horizontal compartment 23 extending between the vertical compartment 21 and the side wall 14 of the container. The back wall 45 may be divided up into several doors, one for each compartment, for the purpose of conveniently removing parcels from the same.

Two vertical guides 35, 36, are provided 50 on the inner face of the door 30, one at each side of the aperture 31, for so guiding the container 10 vertically in front of the inside face of the door that the openings of the several horizontal compartments can be 55 brought in turn into register with the said aperture which is preferably equal to or slightly larger than the opening of the top compartment. These guides may be carried by or integral with the frame 32 if desired. 60 As illustrated, these guides 35, 36 are channels of U-shape in horizontal section, with the open ends of the U directed towards one another. Two ribs in the form of channel members 37, 38, each of U-shape in cross-section, are fixed vertically one to each side of

the container 10 and are arranged to run in said guides 35, 36 with the bottom webs of the U-members 37, 38 lying on the bottoms of the channels 35, 36 so as to make surface contact therewith.

The container 10 is free to fall under gravity between the guides 35, 36, a sudden descent being prevented by the friction of said ribs in the guides, and by shock-absorbers if desired. This friction can be controlled by a regulating device 40 comprising a tubular casing 41 fixed on the guide 35, a plunger 42 in the casing arranged to press on the rib 37, a cap 43 screwed in the outer end of the casing and a spring 44 compressed between the cap and the plunger. 70 75 80

In order to arrest the container in the several positions wherein the horizontal compartments 19, 20, 23 are in register with the aperture 31, escapement mechanism, which may also comprise a shock-absorbing device, is provided. This mechanism, as illustrated, comprises two latches 50, 51 mounted vertically on the flap 33 near its upper edge, one at each end thereof. The underface of the top part of the frame 32 constitutes a keeper plate 52 for the latches and extends inwards towards the container 10 to provide a ledge extending between two recesses shown at 53. These latches are spring-pressed upwards and can extend so far as to enter the recesses 53 and bear against the top member 52 of the frame, as shown in chain lines in Figure 5. Three holding members 54, 55, 56 are hinged to the edge of the top wall 12 and partitions 16 and 17, respectively, adjacent the door 10. These holding members are in the form of long sheet metal plates extending from side to side of the container, hinged thereto at their upper edges and having at their lower edges each two lugs 57, 58 arranged to enter said recesses 53 and bear on the top of the latches 50, 51. These holding members 54, 55, 56 with their lugs constitute detents and are spring-pressed towards the door 30 so as to bear in turn on said ledge 52 and support the container 10 in operative positions, as described hereinafter. 85 90 95 105 110

The receiving apparatus operates as follows:—It will be assumed that the container 10 is empty and in a first or upper operative position as shown in Figure 2. When the flap 33 is opened by a messenger who desires to leave a parcel, such as a bottle of milk, the container will fall a very short distance until it is supported by the detent 56 resting on the ledge 52. After the bottle has been placed in the compartment 21, the messenger will close the flap 33. In so doing the latches 50, 51 will snap behind the top member 52 of the frame 32, as indicated in chain lines in Figure 5, thereby temporarily preventing the flap from being opened, and will also push the detent 56 against its spring control off the ledge 52. Having lost its support the 115 120 125 130

container falls under gravity until it arrives into a second operative position, as illustrated in Figure 4, with the compartment 20 substantially in register with the aperture 31, when the milk bottle has been removed to a place of safety out of reach of a person outside the door 30. In this second position the container is first arrested by the lugs 57, 58 bearing on the latches 50, 51 and pressing them down so far as to release the flap, as shown in Figure 4. When a second messenger arrives he can open the flap 33 and place a parcel in the compartment 20. During such opening of the flap the container is again held by the detent 55 resting on the ledge 52, and on closing the flap 33 the latches 50, 51 will force the detent 55 off its supporting ledge into the position shown in chain lines in Figure 5, so that the container will again fall, whereupon the escapement mechanism can be operated again as described above. The upper compartment 19 can then be used in like manner. When the container 10 falls a third time or the last time of a series of such movements the flap 33 will be latched again and cannot be opened until the container has been lifted, which must be done by a person at the inner side of the door. The last of these downward movements when the top compartment contains a parcel may be not such as to place the opening of the top compartment out of register with the aperture 31 but only such as to place it in a position of rest wherein it is not supported by the latches 50, 51 which consequently lock the flap 33 in its closed position. The latches thus serve not only as locking members for the flap, but also as shock-absorbers for breaking the fall of the container during part of its descent.

It will be understood from the above that the flap 33 is locked in all positions of the container 10 except that wherein an opening of an empty compartment is in register with the aperture 31.

Springs or other cushioning means, such as a dash-pot, may be provided for receiving the container in its lowest position to prevent undue shock, as illustrated at 60 in Figure 1. Also, any convenient form of shock-absorbing device may be provided for arresting the container in each of its upper operative positions. One form of such shock-absorbers is illustrated in Figure 6, which shows a bell-crank lever having a horizontal arm 61 and a vertical arm 62 fulcrumed at 63 on the side of the container. The outer end portion 64 of the arm 61 is knuckle jointed so as to swing freely upwards, and a tension spring 65 tends to hold the arm 62 in a nearly vertical position. Stops 66 are so fixed on the side of the container that when the latter descends a stop will co-act with the part 64 of the arm 61, thereby rocking the lever against the action of its

spring 65 and leaving the lever when the container is just at its next operative position. When the container is lifted and moved in the opposite direction the stops 66 can freely pass the lever without rocking it. 70

In order to prevent the container from being lifted by a person outside the door, a rack 70 having ratchet teeth is provided on the door, for example on the guide 35, and a pawl 71, which may be spring-controlled, 75 is pivoted on the side wall 14 of the container and arranged to engage the rack so as to prevent such lifting.

As illustrated in Figure 7, the pawl 71 has a handle 72 so arranged that when it is desired to lift the container to commence a new cycle of operations, on gripping the handle the pawl is released from the rack and the container can be lifted readily to its upper position. 85

If desired, a spring may be combined with the flap 33 and so arranged as to close it automatically after it has been opened, for inserting a parcel into a compartment, and released, to ensure that the flap shall be returned to its fully closed position after each insertion of a parcel. 90

Provision may be made for ringing a bell or otherwise giving an alarm when the container has descended to its lowest or an intermediate position, so that it may be emptied and reset for receiving further parcels. The press button for such a bell can be operated by the weight of the container. 95

Any convenient arrangement of compartments may be used. Also the container instead of being divided into compartments may have only one opening for registering with the aperture. The operation will then be similar to that described above 100 except that no escapement will be required, but only a single latch, as the container will have to be reset by hand after it has received a parcel. In this case, when the flap is opened the container will descend 110 into its parcel-receiving position in which it permits the flap to be automatically locked when it is closed again after the delivery of the parcel.

Various modifications may be made in the 115 details of construction described above. For example, the container may be arranged to slide horizontally under the action of a spring or weight across the aperture. Also, in some cases a single vertical guide may be 120 provided at only one side of the container, and more than one rack with an associated pawl may be provided. Further it is to be understood that the invention is applicable not only to doors as ordinarily understood, 125 but also to walls or other parts of buildings having an aperture therein, and the term "door" used herein is intended to cover such a wall or part of a building.

I claim;

1. Parcel-receiving apparatus comprising the combination with a wall having an aperture therein, and a closure member for the aperture operable from one side of the wall, of a container having a lateral opening guided to move in proximity to said aperture at the other side of the wall, a support for holding the container in a position ready for the reception of a parcel through the aperture, which container is constrained to move in one direction past said aperture towards said support, and supporting means mounted on said closure member, which supporting means normally serves in the closed position of said closure member to hold the container against movement in said direction, but when the closure member is opened permits the container to move independently of the latter in said direction against said support.
2. Parcel-receiving apparatus comprising the combination with a wall having an aperture therein, and a closure member for the aperture operable from one side of the wall, of a container having a lateral opening guided to move in proximity to said aperture at the other side of the wall, a support for holding the container in a position ready for the reception of a parcel through the aperture, which container is constrained to move in one direction past said aperture towards said support, and a locking device that tends to lock the closure member in its closed position when it has been closed, but normally serves to hold the container against movement in said direction and is thereby held by the container in an unlocking position that permits the closure member to be opened and allow the container to move against said support.
3. Parcel-receiving apparatus comprising the combination with a wall having an aperture therein, and a closure member for the aperture operable from one side of the wall, of a container having a lateral opening guided to move in proximity to said aperture at the other side of the wall, a support for holding the container in a position ready for the reception of a parcel through the aperture, which container is constrained to move in one direction past said aperture towards said support, and a spring-controlled latch that tends to lock the closure member in its closed position when it has been closed, but normally serves to hold the container against movement in said direction and is thereby held by the container in an unlocking position that permits the closure member to be opened and allow the container to move against said support.
4. Parcel-receiving apparatus comprising the combination with a wall having an aperture therein, and a closure member for the aperture operable from one side of the wall, of a container comprising a plurality of compartments having each an opening at the

same side of the container, a support for the container, which container is constrained to move in one direction at the other side of said wall so as to bring the openings of the compartments in succession opposite to said aperture, and escapement mechanism comprising a locking device carried by the closure member, and a plurality of detents, one for each compartment, that are movably mounted on the container, and are controlled by said locking device, and are adapted to co-act successively with said support and thereby retain the container against movement in said direction successively in different positions, in each of which positions one of said compartments has its opening opposite said aperture, which locking device is adapted automatically to lock the closure member closed in all positions of the container except those wherein the container is intended to receive a parcel through the aperture.

5. Parcel-receiving apparatus comprising the combination with a wall having an aperture therein, and a closure member for the aperture operable from one side of the wall, of a container comprising a plurality of compartments having each an opening at the same side of the container, a support for the container, which container is constrained to move in one direction at the other side of said wall so as to bring the openings of the compartments in succession opposite to said aperture, and escapement mechanism comprising a spring-controlled locking device constituting a shock-absorber carried by the closure member, and a plurality of detents, one for each compartment, that are movably mounted on the container, and are controlled by said locking device, and are adapted to co-act successively with said support and thereby retain the container against movement in said direction successively in different positions, in each of which positions one of said compartments has its opening opposite said aperture, which locking device is moved into an unlocking position by a detent supported thereby.

6. Parcel-receiving apparatus comprising the combination with a wall having an aperture therein, and a closure member for the aperture operable from one side of the wall, of a container having a lateral opening movable vertically in proximity to said aperture at the other side of the wall, a support for holding the container in a position ready for the reception of a parcel through the aperture, which container is constrained to move in one direction past said aperture towards said support, and said closure member in its closed position normally holds the container against movement in said direction but when opened permits the same to move independently of it in said direction against said support, two guides of U section, whereof one is

a recess and the other a guide member slidable in the latter, one of which guides is provided on the side of the container and the other on said wall, and means for varying the frictional resistance to movement of one of said guides against the other.

7. Parcel-receiving apparatus comprising the combination with a wall having an aperture therein, and a closure member for the aperture operable from one side of the wall, of a container comprising a plurality of compartments having each an opening at the same side of the container, a support for the container, which container is constrained to move in one direction at the other side of said wall so as to bring the openings of the compartments in succession opposite to said aperture, escapement mechanism comprising a plurality of holding members that are mov-

ably mounted on the container are controlled by the closure member and are adapted to coact successively with said support and thereby retain the container against movement in said direction successively in different positions, in each of which positions one of said compartments has its opening opposite said aperture, and a shock-absorbing device comprising a resiliently-controlled lever-arm fulcrumed on the wall, and a plurality of stops on the container, one for each position in which the container is to be at rest, arranged to coact with the lever-arm and have their movement in said direction checked thereby as the container moves into a position of rest.

In testimony whereof I affix my signature.

SIDNEY HOLE.
